UNITED STATES PATENT OFFICE.

HERON LAMAR CAUDLE, OF WADESBORO, NORTH CAROLINA.

GARMENT SUPPORTER.

1,411,160.

Specification of Letters Patent. Patented Mar. 28, 1922.

Application filed July 26, 1920. Serial No. 399,079.

To all whom it may concern:

Be it known that I, HERON LAMAR CAUDLE, a citizen of the United States, and a resident of Wadesboro, in the county of 5 Anson and State of North Carolina, have invented certain new and useful Improvements in Garment Supporters, of which the following is a specification.

My invention relates to improvements in 10 garment supporters, it being more particularly an improvement on my Patent 1,313,215, dated August 12, 1919, and it consists in the constructions, combinations and arrangement herein described and claimed.

15 One of the foremost objects of the invention is to provide a device for supporting trousers, by the use of which suspenders may be dispensed with entirely and a belt worn for appearances only.

20 A further object of the invention is to provide a garment supporter, made preferably of resilient material and thereby being capable of being sprung and held into position between suitable buttons sewn at the 25 proper places on the inside of the trousers.

A further object of the invention is to provide a device of the character described which is capable of being held in place in 30 a suitably formed pocket on the inside of the trousers.

Other objects and advantages will appear in the following specification, reference being had to the accompanying drawings, in which:

35 Figure 1 is a perspective view illustrating the first act of the user of the supporter in gauging the position of the supporting hook on the shirt.

Figure 2 is a perspective view illustrating 40 the supporting hook as having been fixed in its proper position on the shirt.

Figure 3 is a perspective view showing the garment supporter as having been attached to the hook.

45 Figure 4 is a perspective view illustrating the garment supporter on one side in dotted lines, the proper position thereof being illustrated as in line with the center of the hip.

Figure 5 is a detail perspective view of 50 the garment supporter.

Figure 6 is a perspective view illustrating the garment supporter positioned in a pocket made for the purpose, on the inside of the trousers, and

55 Figure 7 is a detail elevation illustrating a slight modification wherein the lowermost

button slot is replaced by a pendent fabric with a buttonhole.

The garment supporter in Figure 5 consists of a body 1 which is preferably made 60 of rather heavy celluloid but may be made of any other material which produces the requisite quality or resiliency, so that the wings 2 may be contracted by properly gripping the supporter between the fingers and 65 springing the slot 3 over the thread shank of the button 4. Such other material may, for example, consist of light spring steel or other metal.

A pendent wing 5 also has a slot 6 which 70 is intended to receive the shank of the lowermost and central button 7 in the same manner that the other slots receive the other shanks. The reader will observe at once that when the supporter 1 straightens out, 75 due to its resilient properties, the bases of the upper slots will be pushed tightly against the shanks of the buttons and thus hold the supporter in place under all ordinary conditions. 80

Two slots 8 in the body of the supporter 1, carry the elastic loop 9 between them. The lower button slot branches from the lower elastic loop slot as shown. The inner strand of this loop carries the metallic eye 10, there 85 being another metallic eye 11 fixed around the base of that part of the elastic which embraces the eye 10, for the purpose of causing the eye 10 to stand out at an angle of approximately 45°. This position of the 90 eye 10 facilitates placing it over the hook 12 which is affixed to the shirt of the wearer.

The modification in Figure 6 consists in providing a substantially T-shaped pocket P, sewn on the inside of the trousers T but 95 left with an opening O of sufficient extent to enable the insertion of the garment supporter 1 which is now concealed from view, with the exception of the eye 10. Of necessity this eye must be exposed so as to reach 100 the hook 12, there being a slot S in the pocket for the protruding of the eye.

When the pocket P is employed, the buttons 4 and 7 are of course dispensed with, and should it be desired to employ the garment supporter in connection with pocket holders, it may be found desirable to eliminate the slots 3 and 6. It is anticipated, however, that these slots will be formed in all of the garment supporters regardless of 110 whether the supporters are used in connection with pockets P, because instances may

arise where the subsequent use of buttons in place of pockets may be found more desirable.

The modification in Figure 7 consists in attaching the strip 13, of a suitable fabric, to the extremity of the wing 5. This pendent strip has a buttonhole 14 by means of which the wing 5 may be secured from rising by buttoning the strip 13 over a button 7. In this form of the invention the wings 2 are employed the same as before.

The mode of application may be followed in connection with Figures 1 to 4 inclusive. The buttons 4 and 7 are sewn on the inside 15 of the trousers T; they being centered in respect to the trousers seam so that the supporter 1 is nicely balanced on the hip of the wearer. The wings 2 are then grasped by the fingers, bowed and sprung in place 20 over the shank of the button 4. The lower slot is then fitted over the single button 7 afterwards.

The wearer now gauges the approximate position of the hook 12 on his shirt, by 25 conveying the eye 10 over in the direction of the arrow a. Having properly gauged the position, the hook 12 is secured to the shirt as shown in Figure 2, the hook preferably having the well-known "Boston" type of 30 fastening.

In supporting the trousers on the hook 12, they may either be grasped as suggested in Figure 2, or the eye 10 may be taken in the fingers and lifted over the hook. Figure 3 shows the supporter in position on the hook, one side of the trousers being drawn out in order to illustrate the application.

Figure 4 illustrates the supporter in position in dotted lines. It is to be observed that 40 the supporter is well centered on the hip and thereby makes a comfortable and secure sustainer for the trousers.

While the construction and arrangement 45 of the improved garment supporter as herein described and claimed is that of a generally preferred form, obviously modifications and changes may be made without departing from the spirit of the invention or the scope of the claims.

50 I claim:

1. A supporter, comprising a body with a certain part having openings, the body be-

ing of resilient material to enable springing the openings over companion supporting means on a garment, an elastic band 55 looped through portions of said body, a button opening being formed in another part of the body, and an eye carried by the band for engaging a fastening on an upper garment.

2. A supporter, comprising a body having oppositely extending wings and a pendent wing, all with end slots, the body being made 60 of resilient material to enable springing the slots over fastening means on a lower garment; an elastic band mounted on the pendent wing, including means for its adjustment; and an eye carried by the band for engaging fastening means on an upper garment.

70 3. A supporter, comprising a body having oppositely extending wings and a pendent wing, all with end slots, the body being made 75 of resilient material to enable springing the slots over fastening means on a lower garment; an elastic band mounted on the pendent wing, including means for its adjustment; an eye carried by the band for engaging fastening means on an upper garment, and means carried by the band causing 80 the eye to stand at an angle in respect to the supporter to facilitate engagement to the supporter with said fastening means.

4. Garment supporting means, comprising 85 the combination of a pocket, with an opening, secured on the inside of a garment; and a supporter inserted into the pocket through said opening and completely inclosing the supporting means, including an elastic band carrying an eye protruding 90 through a slot in said pocket, for engagement with fastening means on an upper garment.

5. A supporter, comprising a body with 95 oppositely extended wings and a pendent wing, the former having end slots for engagement with fastening means on a garment when the body is sprung, an elastic band, with an eye, carried by the pendent wing; and a fabric extension secured to 100 the pendent wing, with a buttonhole enabling securing the pendent wing to fastening means on said garment.

THERON LAMAR CAUDLE.
